UNITED STATES PATENT OFFICE

155,391

DESIGN FOR A LUGGAGE CARRIER FOR MOTORCYCLES

Anthony T. Comiskey, Sr., and Charles A.
Comiskey, Chicago, Ill.

Application July 10, 1947, Serial No. 140,196

Term of patent 14 years

(Cl. D90—3)

To all whom it may concern:

Be it known that we, Anthony T. Comiskey, Sr., and Charles A. Comiskey, citizens of the United States, residing in Chicago, in the county of Cook and State of Illinois, have invented a new, original, and ornamental Design for a Luggage Carrier for Motorcycles, of which the following is a specification, reference being had to the accompanying drawings, forming part thereof.

The figure is a perspective view of a luggage carrier for motorcycles, showing our new design. The broken line showing of a motorcycle fender on which the carrier is adapted to be mounted is for illustrative purposes only.

We claim:

The ornamental design for a luggage carrier

for motorcycles, substantially as shown and described.

ANTHONY T. COMISKEY, SR.
CHARLES A. COMISKEY.
